LOCKING APPARATUS

Kenneth J. J. McGowan, Pittsburgh, Pa., assignor
to Westinghouse Air Brake Company, a corpo-
ration of Pennsylvania

Application May 6, 1948, Serial No. 25,327

11 Claims. (Cl. 246—161)

1

My invention relates to locking apparatus adapted for use in railway signaling. More particularly, my invention relates to apparatus for locking railway track switches and incorporating a padlock, an electric circuit controller operable as soon as the padlock is removed, and a mechanical timer which prevents operation of the switch for a predetermined time after the circuit controller is operated.

It is customary in railway signaling and traffic controlling systems to provide locks for preventing unauthorized operation of railway track switches located outside the limits of interlocking plants. Such a lock is usually mounted on the ties adjacent to a track switch, and locks a member so connected with the points of the switch that the points can be moved only when the member is free to move.

Where the switch is one which controls traffic from a siding onto a main line over which high speed trains are running, the switch is of course locked in its normal position which permits movement over the main line and prevents movement to or from the siding. It is desirable to prevent an operation of the switch which would permit movements onto the main line without giving the main line trains warning of such switch operation. To secure such protection for main line trains, the locking device for the switch may be provided with an electrical circuit controller and a time delay device in addition to the usual padlock. The lock is so arranged that when the padlock is removed, a preliminary movement of an operating member on the lock either automatically takes place or may be manually made. This movement operates the circuit controller and starts the time delay device running, but does not unlock the switch. The circuit controller is connected with the signaling system so as to set the signals on the main line at stop when this preliminary movement is performed. The time delay device starts running at the same time and after a predetermined period, for example, 3 minutes, it releases the operating member so that its unlocking movement may be completed. The switch may then be moved from its normal to its reverse position. The length of the time delay is chosen to be sufficient either for any train which has passed the nearest adjacent signal to move on past the switch before it is thrown, or to permit stopping of any train which is approaching the nearest signal at the time that signal is set to stop by operation of the circuit controller. After the movement through

2

the switch is over, the switch and the lock must be restored to their respective normal positions, and the lock must be padlocked in order that the main line signals may be restored to normal. By the use of a locking device equipped with a circuit controller and a timer of the type described, operation of the siding switch may be prevented from dangerously interfering with traffic on the main line.

10 I have shown in my copending application for Letters Patent of the United States, Serial 734,273, filed March 12, 1947, now U. S. Patent No. 2,520,848, for Locking Devices, a locking device of the type described, including a circuit controller operated by a preliminary movement of a lock mechanism and a mechanical timer which maintains the track switch locked for a predetermined time after operation of the circuit controller. The locking device shown in my 15 said copending application is termed a high-type lock, since it is operated by hand and is mounted on a stand which projects several feet above the level of the trackway.

20 In some cases, it may be desired to use such a switch lock in a location where the clearance requirements will not permit use of a high-type lock. Where a low-type lock is used, it is desirable that its external operating parts be arranged so that their proper mode of operation is readily apparent to a switchman. Such an arrangement avoids unnecessary delays in unlocking the switch and in reapplying the padlock after the movement through the switch is over.

25 30 35 It is therefore an object of the present invention to provide an improved low-type lock mechanism suitable for use in connection with railway track switches.

Another object is to provide locking apparatus 40 of the type described which is smaller and more compact than previous locking devices.

45 A further object is to provide an improved foot pedal arrangement for a low-type lock, in which the parts of the mechanism associated with the padlock are clearly visible to the operator in all positions of the apparatus.

50 Another object of my invention is to provide a low-type switch lock including a foot pedal and a casing containing the locking mechanism, including an improved arrangement for transmitting motion between the pedal and the interior of the casing incorporating an improved seal for preventing the entrance of dirt and moisture into the casing.

55 I accomplish these objects of my invention by

providing a casing containing the locking mechanism and having mounted thereon a single external operating member including two foot pedal portions projecting therefrom. One foot pedal near the lower part of the lock is used to operate the locking mechanism to its unlocked position. The other foot pedal is used to restore the mechanism to its locked position and is mounted near the top of the operating member where it is clearly visible at all times to a person operating the devices. The operating member is also provided with an eye which fits over a staple adapted to receive the bail of a padlock and mounted on a fixed portion of the apparatus. This eye is also placed near the upper end of the operating member. The eye and the staple are also clearly visible to an operator in all positions of the operating member.

The operating member is mounted for rotary movement on an arbor which extends through an aperture in a wall of the casing. Inside the casing a rotary locking member is also mounted on the arbor. This rotary member extends through the aperture and engages the operating member so that the two rotate concurrently. The operating member is provided with an annular surface which sealingly engages the peripheral surface of the aperture through which the arbor and the rotary member pass. The seal between the operating member and the inside of the casing is therefore between two relatively rotating surfaces and is inherently better than a seal between two relatively sliding surfaces.

The casing is also provided with an external jaw to receive the hand-throw lever of a railway switch when the lever is in its normal position. A latching arm on the lock operating member is provided. When the operating member is in its padlocked position, this latching arm extends over the jaw so that the hand-throw lever may not be withdrawn. A compact spring basket arrangement inside the casing is connected to the rotary member, so that when the padlock is removed, the rotary member and the operating member are moved to an intermediate position by the spring basket. In this intermediate position, the latching arm of the operating member still prevents movement of the hand-throw lever. A locking dog within the casing extends into the path of a portion of the rotary member and prevents its movement beyond this intermediate position in an unlocking direction. This locking dog is operated by a mechanical timer, including a clockwork mechanism. The timer is wound up by a cam associated with the rotary member as the operating member is moved from its intermediate to its padlocked position. When the operating member is moved from its padlocked to its intermediate position, the timer is released by the cam. After the expiration of a predetermined period of time for which the mechanical timer is preset, it snaps the locking dog out of the path of the rotary member to permit movement of the operating member to its unlocked position so that the hand-throw lever of the switch may then be operated from its normal position to its reverse position.

In order to make the timer as small as possible, a timer is used which produces only a small amount of mechanical movement. Since a relatively greater movement is required of the locking dog in order that its operation may be

positive, I mount the timer at one end of the casing and the locking dog and the rotary member at the other end of the casing. An elongated motion multiplying lever connects the timer with the locking dog.

The intermediate portion of the casing between the two ends is occupied by an electrical circuit controller operated by a cam on the rotary member. This circuit controller is operated from one circuit controlling position to another as the operating member is moved from its padlocked to its intermediate position. The cam and follower which operate the circuit controller are provided with opposed surfaces, so that the circuit controller is positively operated in both directions.

The follower which operates the circuit controller is provided with an extending finger which engages and forces the locking dog into its locked position when the operating member is returned to its padlocked position. Failure of the mechanism to operate properly because of sticking of the locking dog in its released position is thereby prevented. Also, if the lock mechanism is broken so that the locking dog cannot be restored to its locking position, this finger prevents restoration of the operating member to its padlocked position. The apparatus therefore fails safe, since the main line signals must remain at stop if the lock is broken. An indicator is mounted on the arm which operates the locking dog and is visible through an aperture in the casing to indicate to the operator of the device whether the locking dog is in its locked or unlocked position.

The casing is provided with a cover having depending edges which provide a deeply recessed central portion. The circuit controller is attached by means of a bracket to the casing. The bracket extends inwardly and upwardly of the casing so that the terminal board of the circuit controller is within the recessed cover. When the cover is open, the terminal posts and the contacts of the circuit controller are therefore readily accessible.

Other objects and characteristic features of my invention will become apparent as the description proceeds.

I shall describe one form of locking apparatus embodying my invention, and shall then point out the novel features thereof in claims.

In the accompanying drawings, Fig. 1 is a plan view of the switch lock embodying my invention applied to the hand-throw lever of a railway track switch. Fig. 2 is a front elevational view, on a larger scale, of the switch lock shown in Fig. 1. Fig. 3 is a cross sectional elevation taken on the line III—III of Fig. 6, with certain parts removed and others broken away for the sake of clarity. Fig. 4 is a fragmentary cross sectional view taken on the line IV—IV of Fig. 6, illustrating the details of the spring biasing mechanism. Fig. 5 is a fragmentary cross sectional view taken on the line V—V of Fig. 3, illustrating certain constructional details. Fig. 6 is an elevational view taken substantially on the line VI—VI of Fig. 3 with certain parts omitted and others broken away. Fig. 7 is a fragmentary cross section, on a larger scale, taken on the line VII—VII of Figs. 3 and 6. Fig. 8 is a rear elevational view showing details of construction of the time release mechanism illustrated in Figs. 3 and 6. Fig. 9 is a view showing the obverse face of the time release mecha-

nism shown in Fig. 8. Fig. 10 is a vertical sectional view taken on the line X—X of Fig. 8.

Referring to the drawings, there is shown a switch lock constructed in accordance with my invention and including a casing 1 having a cover 2 attached thereto by means of hinges 3. The casing 1 is attached to a mounting plate 4 by means of bolts. The mounting plate 4 is in turn attached to the ties of a railway. Also attached to the mounting plate 4 is a stand 5 forming a part of a switch machine. The complete switch machine is not shown. The stand 5 supports a bearing 6 which carries a switch operating shaft 7. A hand-throw lever 8 is attached to the end of shaft 7.

The casing 1 is provided with two spaced extensions 9 and 10 which terminate respectively in upstanding posts 11 and 12. The posts 11 and 12 together with extensions 9 and 10 form a jaw for receiving the hand-throw lever 8 when it is in its normal position as shown in Fig. 1. A lock rod 13 is eccentrically attached to shaft 7, and extends into an aperture 11a in the post 11, for a purpose to be later described.

A latch member 14 is pivotally mounted between the extensions 9 and 10 of casing 1 on an arbor 15 (see Figs. 3, 5, and 6). The latch member 14 includes a latching arm 14a, an outwardly projecting pedal arm 14b, an upwardly and laterally projecting pedal wing 14c, and an extension 14d having an eye 14e therein for receiving a padlock staple 16 attached to an extension 11b on the post 11. A padlock 16a is shown in Fig. 3 with its ball extending through staple 16.

The casing 1 is formed with a hollow projection 9a (see Fig. 5), which is a part of the extension 9 and which forms a recess 9b in the interior of the casing. The side of projection 9a nearest the center of the casing 1 is provided with an aperture 9c. The extension 10 on the casing includes a wall 10a parallel to and spaced from the wall of projection 9a in which the aperture 9c is located. The arbor 15 passes freely through aperture 9c, and is supported at its opposite ends in the wall 10a and in the wall of projection 9a, opposite the aperture 9c. The wall 10a and the wall containing the aperture 9c define the opposite sides of an external recess 10b in the wall of casing 1. The latch member 14 is pivotally mounted on the arbor 15 within the external recess 10b. Within the internal recess 9b, a rotary member 17 is rotatably mounted on the arbor 15. The rotary member 17 is provided with teeth 17f (see Fig. 5) which project through the aperture 9c and engage corresponding teeth 14f in the latch member 14, so that the latch member 14 and the rotary member 17 rotate together. Latch member 14 is provided with an annular flange 14g which engages the peripheral surface of the aperture 9c, and seals that aperture against the entry of dirt and moisture from the outside of the casing.

Inside the casing 1, the rotary member 17 carries a cam projection 17a (see Figs. 3 and 6) having oppositely tapered end surfaces 17b and 17c. These end surfaces are adapted respectively to engage arms 18a and 18b on a pivotally mounted follower 18. The rotary member 17 also carries another cam 17d, which cooperates with a follower 19 carried by an arm 20 rotatable on a shaft 21.

The rotary member 17 also carries a pin 22 which supports one end of a spring basket arrangement shown in detail in Fig. 4.

This spring basket arrangement includes an 75 threaded into the flanges. The terminal board 44

external sleeve 23, which is bifurcated at one end to form spaced lugs, one of which is shown at 23a. The lugs 23a are apertured to receive the pin 22. The pin 22 may be held in the lugs 23a by any suitable means (not shown), as for example, cotter pins. The sleeve 23 is provided at one end with an internal flange 23b. A collar 24 is threaded on the external surface of the opposite end of sleeve 23. The collar 24 carries another internal flange 24a. The collar 24 and the sleeve 23 freely receive an eye bolt 25 on which is threaded a sleeve 26. The eye end of eye bolt 25 extends outside the end of sleeve 23 opposite the pin 22, where it receives a pin 27, which is fixed in a suitable boss 27a (see Fig. 6) on the casing 1. The end of sleeve 26 nearest the pin 22 is formed with an external flange 26a. A pair of lock nuts 28 are threaded on the exterior of the opposite end of sleeve 26 and in effect form another external flange. A pair of spring retaining washers 29 and 30 are slidably received on the exterior of sleeve 26, and slide within the sleeve 23. A coil spring 31 surrounds the sleeve 26 and is retained thereon by the washers 29 and 30.

The parts of the spring basket mechanism are arranged so that the distance between the external flanges 26a and 28 on sleeve 26 is the same as the distance between the internal flanges 23b and 24a on sleeve 23. Therefore, when the parts are positioned so that flange 23b is aligned with flange 26a, then flange 24a is aligned with flange 28. Under such conditions, the spring 31 exerts no biasing force on pin 22, and any movement of pin 22 toward or away from pin 27 causes spring 31 to be compressed. This position of pin 22 is referred to hereafter as its neutral position.

The parts are shown in Fig. 4 in the position they assume when the pin 22 has been moved toward pin 27 from its neutral position. The sleeve 23 has been moved toward the pin 27 carrying the retaining washer 29 with it and compressing the spring 31 against the washer 30 which is held by nuts 28 on the sleeve 26. With the parts in the position shown in Fig. 4, therefore, the spring 31 biases the pin 22 toward the left and thereby biases the rotary member 17 for movement in a counterclockwise direction.

The cam follower 18 is pivotally mounted on a shaft 32 (see Fig. 6), which is journaled in two bearings 33 formed in lugs 33a extending from the casing 1. An operating member 35 for a circuit controller generally indicated at 36 is integrally attached to the follower 18. The operating member 35 is channel-shaped, and is supported on the shaft 32 by means of a pair of arms 37. Fixed in the channel of the operating member 35 are three insulating strips 38, 39, and 40, which extend longitudinally of the channel-shaped operating member 35 so as to form two spaced slots 41 and 42.

A generally U-shaped bracket member 43 is attached at its ends to one side of the casing 1 and extends upwardly and inwardly so that the bight of the bracket member extends across the central portion of the cover 2. The cover 2 is provided with downwardly depending side portions so that it is deeply recessed, and the bracket member 43 extends upwardly into this deep recess. Each end of the bracket 43 is provided with oppositely projecting flanges 43c and 43d. An insulating terminal board 44 is attached to the flanges 43c by means of screws 45 which are threaded into the flanges. The terminal board 44

is of conventional construction. It carries a plurality of terminal posts 46 and a plurality of downwardly depending stationary contacts 47, each of which cooperate with a similar downwardly depending movable contact 48. The movable contacts 48 extend downwardly into the insulating slot 42 formed in the circuit controller operating member 35. Each flange 43d on the bracket 43 carries a short terminal board 49. Each of the two terminal boards 49 carries two terminal posts 46, one downwardly depending stationary contact 51, and one downwardly depending movable contact 52. The movable contact 52 extends downwardly into the insulating slot 41 formed in the circuit controller operating member 35.

A downwardly depending lug 43e is formed on the bracket 43 and extends between the short terminal boards 49. The lug 43e supports a bracket 54, on which is pivoted an indicator 55, which is visible from outside the casing through an aperture 2a in the cover 2. The indicator 55 is operated by a rod 56 which is pivoted at its opposite end on an arm 57. The arm 57 carries at its end a locking dog 58, which in the position shown in the drawings, lies in the path of a projection 17e (see Fig. 3) on the rotary member 17. The locking dog 58 is provided with a laterally extending lip 58a which engages a lug 59 formed on the housing 1 to limit the downward movement of the locking dog. The follower 18 carries a force-down finger 18c which at times is effective to force the dog 58 downwardly and bring it into the path of projection 17e.

The locking dog 58 may be moved out of the path of projection 17e on rotary member 17 by means of a mechanical time release arrangement including a timer generally indicated at 60 in Figs. 3 and 6 and a snap action latching mechanism generally indicated at 61. The timer 60 and the latch 61 are illustrated in detail in Figs. 7, 8, 9, and 10. This timer and latch are described and claimed in my copending application Serial No. 734,273, previously mentioned.

The timer 60 is provided with an operating push rod 62 whose lower end is enclosed by a cap nut 63. The push rod 62 is operated by an arm 64 (see Figs. 6 and 8) connected to a rod 65 which is attached at one end to the arm 20 and at its opposite end to an arm 66, which, like arm 20, is pivotally mounted on the shaft 21. Shaft 21 is supported at one end by a lug 67 which projects from the wall of casing 1 and at its opposite end by a lug 68 which projects from a wall of casing 1.

The time release mechanism 60 is best shown in Figs. 8, 9 and 10. It comprises a housing 69 mounted on a frame 101 which is fastened by screws to supporting lugs 70 attached to casing 1. Push rod 62 is slidably mounted at its upper end (see Fig. 10) in a cap member 71 threaded into an opening provided in the top member of housing 69, and projects through an aligned opening 72 provided in the lower member of housing 69. The mounting or rod 62 permits up and down movement but preferably rotational movement of the rod is prevented by providing it with a square or hexagonal shape in that portion of the rod that projects through opening 72, and by forming that opening with a corresponding shape. A coil spring 73 surrounds the upper end of rod 62 and is confined between cap member 71 and a shoulder formed on rod 62 so as to bias the rod constantly to its lowermost position. The rod 62 is operatively connected through a gear train with

6 an escapement mechanism in such a manner that operation of the rod upwardly against the bias of spring 73 can be effected freely but operation of the rod downwardly in response to the bias of the spring is controlled by the escapement mechanism.

The gear train and escapement mechanism are mounted on shafts carried in bearings provided in front and back plates 74 and 75, respectively, 10 which are secured by screws to housing 69 to enclose the working elements of the mechanism. Rod 62 is operatively connected with the gear train by means of a segment gear 76 mounted on a shaft 77 and provided with an integrally formed crank 78 carrying a pin 79 which engages a slot 62a provided on rod 62, the arrangement being such that any movement of rod 62 is communicated to gear 76 by means of the movement of pin 79 and crank 78 caused by slot 62a.

20 Segment gear 76 is connected through a train of gears, with an escapement wheel 80 mounted on a shaft 81. The train as shown includes a pinion 82 meshing with segment gear 76 and mounted on a shaft 83. Shaft 83 carries a rotatably mounted gear 84 having a pair of pawls 85 (see Fig. 9) biased by springs 86 into engagement with the teeth of a ratchet wheel 87 fixed on shaft 83 in juxtaposition with gear 84. The pawls 85 and wheel 87 cooperate to permit wheel 87 to be 30 rotated in a clockwise direction (as viewed in Fig. 9) without effecting rotation of gear 84, but effect rotation of that gear in the event that wheel 87 operates in a counterclockwise direction. Gear 84 meshes with a pinion 88 carried on a shaft 89. 35 A gear wheel 90 is fixed on shaft 89 and engages a pinion 91 fixed on shaft 81 carrying the previously mentioned escapement wheel 80.

A rockshaft 92 carries an escapement lever 93 having pawls which cooperate with the teeth of escapement wheel 80. Lever 93 has a slotted arm 93a engaging a driving pin 94 carried on a balance wheel 95 mounted on a shaft 96 and connected with a hair spring 97, the arrangement being such that rotation of escapement wheel 80 is converted into reciprocating motion of escapement lever 93 which acts through its slotted arm 93a and pin 94 to cause balance wheel 95 to oscillate in opposition to hair spring 97. The pawls of lever 93 are shaped to provide self-starting features 50 for the escapement mechanism, by coacting with the teeth of wheel 80 to impose a torque on lever 93 effective in all positions of wheel 80 to cause balance wheel 95 to oscillate. In this arrangement, shaft 96 and escapement lever 93 are disposed with respect to each other and proportioned so that the extreme upper end of lever arm 93a oscillates through an arc passing through shaft 96 just short of its axis. In order to permit oscillation of lever 93 past shaft 96, a portion of 60 the shaft is relieved by slotting to its axis, as at 96a (see Fig. 9), with the slot having a flat surface perpendicular to the radius of wheel 95 passing through driving pin 94. Lever 93 will oscillate past shaft 96 only when the slot of the shaft 65 provides clearance for the lever, and this occurs only during the interval that the slotted portion of the shaft is disposed with its flat surface substantially tangent to the arc of lever arm 93a and with its unrelieved portion extending radially outward from that arc. When balance wheel 95 in oscillating rotates shaft 96 slightly away from the position mentioned, the unrelieved portion of shaft 96 then projects into the path of lever 93 to restrain movement of the lever past the shaft, thereby periodically interrupting its movement

to restrain rotation of escapement wheel 80. In this arrangement, therefore, the step-by-step control of escapement wheel 80 is established by the cooperation of lever arm 93a with the slotted shaft 96, and the oscillation of balance wheel 95 is effective to move the unrelieved portion of shaft 96 into and out of the path of lever arm 93a.

The portion of rod 62 that projects downwardly from housing 69 is threaded to receive an operating nut 62b which may be adjusted to assume a wide range of positions on the rod. The rod 62 is positioned by the driving arm 64, as previously described. Arm 64 is connected through rod 65 to a cam follower 19 engaging the cam 17d provided on rotary member 17 for operatively connecting the latch member 14 with push rod 62 of time mechanism 60.

When latch member 14 is in its normal position as represented in the drawings, cam 17d operates through follower 19 and the upper driving surface of arm 64 to hold cap nut 63 and rod 62 to their uppermost positions, in which they are illustrated in the drawings, in opposition to the bias of spring 73. When rotary member 17 is rotated counterclockwise a few degrees from the position shown in Fig. 3, the driving surface of cam 17d is removed from follower 19, which then drops and moves arm 64 clear of nut 63 and permits rod 62 to be driven downwardly by spring 73 at a rate determined by the escapement mechanism and its associated gear train, the segment gear 76 in this case rotating shaft 83 in such a direction as to drive gear 84 and ratchet wheel 87 so as to bring into play the operation of the escapement mechanism previously described. This movement of rod 62 causes a corresponding movement of operating nut 62b which functions in a manner to be explained hereinafter to trip off a tripping mechanism. The latter mechanism may be arranged to limit the downward travel of rod 62. When latch member 14 is restored to its normal position cam 17d drives follower 19 upwardly so that arm 64 forces rod 62 to its uppermost position, the rotation of shaft 83 effected by gear 76 in such event being in the direction which permits ratchet wheel 87 to rotate freely without driving gear 84 so that the escapement mechanism is removed from operation at this time.

The time release mechanism 60 is arranged so that it can be removed as a unit from the locking device. This removal may readily be effected merely by unscrewing housing 69 from its support, and lifting the mechanism away from the support. The arrangement greatly facilitates inspection and repair of the timing unit, and not only permits the timing mechanism to be replaced as a unit but also enables the unit to be packaged separately for shipment apart from the remainder of the lock so that the unit may be assembled in operative relation in the lock after the casing has been installed at its point of use. This removable feature of the timing unit affords protection for the bearings and pivots of the unit against shock and vibration damage incident to the shipment and installation of the lock device.

Additional protection against shock and vibration is provided in the timing unit by means of leaf springs 113 (see Figs. 8 and 9) carried by a spring arm 114 fastened to plunger rod 62. The springs 113 are proportioned to engage the shafts of the gear train and escapement mechanism of the unit when rod 62 is in its uppermost position, and thereby impose a spring load on the respective shafts. When rod 62 moves downwardly,

the corresponding movement of spring arm 114 removes the spring loading from the shafts so that the shafts rotate freely in their bearings. The spring loading is effective in the uppermost position of rod 62 to prevent damage to the bearings and pivots due to shock and vibration resulting from trains passing the point of lock installation, consequently the delicate parts of the timing unit are protected against damage from the severe vibrational disturbances to which the parts necessarily are exposed when installed for use on ties supporting the adjacent trackway.

The locking dog 58 previously mentioned forms a part of the locking means and, when disposed in the path of shoulder 17e of rotary member 17, limits movement of latch member 14 so that latching arm 14a remains in the path of the hand-throw lever 8. The dog 58 is operatively connected with the time release mechanism 60 through the tripping mechanism 61. The mechanism 61 is effective when tripped to operate dog 58 out of the path of shoulder 17e so that latch member 14 is then free to rotate so as to move latch arm 14a out of the path of hand-throw lever 8, and the switch is unlocked. The tripping mechanism cooperates with the time release mechanism 60 to retain dog 58 in its full down position in the path of shoulder 17e until after the expiration of a predetermined time, following which the tripping mechanism is tripped by mechanism 60 to operate dog 58 with a snap action to its unlocking position out of the path of shoulder 17e.

The tripping mechanism is shown best in Figs. 35 and 10. Locking dog 58 is mounted at the extreme end of arm 57, which is carried by a clevis 98. Clevis 98 has spaced fingers 98a (see Fig. 7), by which it is pivotally supported on a pin 99 journaled in depending lugs 100 provided on supporting frame 101 of the timing mechanism 60. Clevis 98 is also provided with an opening 98b in which a spring 102 is compressed between top and bottom plates 103 and 104. The top plate 103 bears against a shoulder formed in opening 98b. Lower plate 104 bears against a pin or cotter key 105 carried in suitable holes in the side walls of the opening.

An adjusting bolt 106 is provided for engaging top plate 103 to compress spring 102 and thereby impose a spring load on clevis 98, arm 57 and dog 58 to bias that dog downwardly and hold lip 58a (see Fig. 3) in engagement with lug 59. Bolt 106 is carried by a latch lever 107 also having spaced arms 107a by which it is pivoted on pin 99. Latch lever 107 has an upwardly extending finger 107b adapted to be engaged by a finger 108a on a retaining lever 108 pivoted on a pin 109 journaled in lugs 108a provided on frame 101. Another arm 108b of retaining lever 108 is biased by a spring 110, confined between that arm and frame 101, to the position where finger 108a engages finger 107b of latch lever 107.

An operating lever 111 also pivoted on pin 19, is provided with a lug 111a which cooperates with a lug 98c on clevis 98 to confine a spring 112, the arrangement being such that spring 112 tends to force clevis 98 and lever 111 to rotate in opposite directions about pin 99. An arm 111b of operating lever 111 is adapted to engage arm 108b of retaining lever 108 to rotate that lever in a counterclockwise direction (as viewed in Fig. 10) against the bias of spring 110, the rotation of retaining lever 108 being effective to move finger 108a out of engagement with finger 107b of latch lever 107. Another arm 111c of

operating lever 111 is provided for engaging operating nut 62b of time release mechanism 60, the arrangement being such that in the normal positions of the parts as shown in Fig. 10, nut 62b is disengaged from arm 111c so that operating lever 111 is in its normal position, arm 111b engages arm 108b of retaining lever 108, the other arm 108a of retaining lever 108 engages finger 107b of latch lever 107, and bolt 106 depresses top plate 103 to impose a spring bias on arm 98, forcing locking dog 58 downwardly into the path of shoulder 17e.

Operating lever 111 is also provided with a lug 111d which in the normal position of the lever engages a cooperating lug on lever 107. When rod 62 moves downwardly, nut 97 engages arm 111c of operating lever 111 to rotate that lever in a clockwise direction about pivot pin 99, thereby compressing spring 112 confined between lugs 111a and 98c. At the same time, arm 111b of lever 111 rotates retaining lever 108 in a counterclockwise direction about its pivot pin 109 and causes arm 108a to move out of engagement with finger 107b of latch lever 107. When this happens, the parts are tripped so that bolt 106 no longer applies a force to upper plate 103 on arm 98, and the energy stored in springs 102 and 112 is effective to rotate clevis 98 in a clockwise direction about pin 99 and snap dog 58 out of the path of movement of shoulder 17e. A stop lug provided on the end of arm 108b of lever 108 engages frame 101 to limit the rotation of lever 108 and through it, the rotation of lever 111 and consequently the downwardly travel of nut 62b of the time release mechanism.

Operation

The parts are shown in the drawings in their normal, or locked, positions. When it is desired to release the switch lock, so that the switch connected to the hand-throw lever 8 may be thrown from its normal to its reverse position, the switchman first removes the padlock 16a from the staple 16. This permits the latch member 14 to rotate counterclockwise as viewed in Fig. 3, under the influence of the biasing spring 31. The parts of the spring basket mechanism connected with spring 31 are so arranged that the neutral position of pin 22 corresponds with an intermediate position of latch member 14 and rotary member 17 in which the projection 17e on rotary member 17 is engaging the locking dog 58. The spring 31 is therefore effective upon removal of the padlock to move the latch member 14 and rotary member 17 to their respective intermediate positions. As the rotary member 17 travels through this distance, the cam surface 17b engages the follower surface 18a and rotates follower 18 clockwise sufficiently far to move the circuit controller operating member 35 so as to operate the movable contacts 48 and 52 from one circuit controlling position to another. This operation of the circuit controller either shunts the track circuit associated with the switch or performs some other circuit controlling function so as to set the signals associated with the main line track approaching the switch at stop.

At the same time that the circuit controller is so operated, the cam 17d moves out from under follower 18, allowing the latter to drop, and thereby allowing the finger 64 to fall away from the cap nut 63 on the lower end of the timer operating push rod 62. The push rod 62 then starts to move downward, its rate of movement

being controlled by the timer 60. When the time determined by adjustment of timer 60 has elapsed, the downward movement of nut 62a trips the latch mechanism 61, thereby operating the lock dog 58 upwardly out of the path of movement of rotary member 17.

In the intermediate position of the latch member 14 and rotary member 17, the latch arm 14a still remains in the path of hand-throw lever 8, so that the latter cannot be removed from the lock mechanism. As soon as the locking dog 58 is moved out of the path of rotary member 17, the switchman may then rotate the latch member 14 further in a counterclockwise direction by stepping on the pedal 14b, thereby forcing the latch member 14 against the tension of spring 31 to a position wherein the latch arm 14a is withdrawn from the path of movement of the hand-throw lever 8. The switchman may then lift the hand-throw lever 8 from the lock and throw the switch. As the hand-throw lever 8 is so lifted, the lock rod 13 is operated by the eccentric on shaft 7 to move through the apertures 11a and 12a, thereby preventing any return movement of the latch member 14 to its latched position until the hand-throw lever is restored to the position shown in the drawings.

When the hand-throw lever is restored to its normal position, the lock rod 13 is removed from the path of the latching member 14, which then returns to its intermediate position under the influence of spring 31. The switchman then restores the latching member 14 to its normal position by pushing on the pedal 14c, and again applies the padlock through the staple 16. This movement of the latching member 14 from its intermediate position to its normal position restores the circuit controller contacts to their normal position, and winds up the spring in the timer 60 through the action of cam 17d on follower 19.

The indicator 55 informs the switchman as to the position of the locking dog 58. As long as the locking dog limits movement of rotary member 17, the indicator reads "Locked." When the locking dog 58 is moved upwardly out of the path of rotary member 17, the indicator 55 moves upwardly with it, carrying the legend "Unlocked" into view. The switchman then knows that he may release the hand-throw lever 8 by stepping on the pedal 14b.

It should be noted that the locking dog 58 lies between the projection 17e on rotary member 17 and the lug 59 on the casing. The locking dog 58 is thereby backed up by the casing so that it cannot be injured by a switchman who rests his weight on the pedal 14b while waiting for the locking dog 58 to be released by the latch mechanism 61.

As the rotary member 17 is returned from its intermediate position to its normal position, the force down finger 18c engages the upper surface of locking dog 58 and forces it down into its locking position. Sticking of the timer or latch mechanism is thereby prevented from causing improper operation of the switch lock. In case the mechanism is so jammed that the locking dog 58 cannot be restored to its normal position, then the finger 18c prevents restoration of the circuit controller 36 to its normal position, so that the signals remain at stop until the trouble is remedied. It may therefore be seen that the switch lock mechanism I have described fails safe.

Although I have herein shown and described

only one form of locking apparatus embodying my invention, it is understood that various changes and modifications may be made therein within the scope of the appended claims without departing from the spirit and scope of my invention.

Having thus described my invention, what I claim is:

1. An apparatus for locking a throw lever, the combination comprising a casing, a jaw projecting from the casing for receiving the lever, a hollow projection on said casing forming a recess in an interior wall thereof, said casing having an external recess adjoining said interior recess and an aperture in the casing wall between the two recesses, an arbor extending freely through said aperture and supported by the two recess walls opposite the apertured wall, a member rotatably mounted on the arbor in said interior recess, a latch member rotatably mounted on the arbor in said external recess, one of the members having a portion thereof projecting through the aperture and engaging the other member so that the two members rotate concurrently, said latch member being movable between a first position wherein it projects into the jaw to prevent movement of the throw lever therefrom and a second position wherein the latch member is withdrawn from the jaw, lock means inside the casing for limiting rotation of the interior member to prevent movement of the latch member to its second position, and means in the casing for releasing the lock means.

2. The combination as set forth in claim 1 including an annular flange on the latch member sealingly engaging the periphery of the aperture to prevent entry of dirt into the casing.

3. Apparatus for locking a movable member comprising a casing, a jaw on the casing for engaging the member, a latch pivotally mounted on the casing, a rotary member in said casing and directly connected to the latch for concurrent movement therewith, said latch and rotary member being movable between two extreme positions, said latch being effective when in a range of positions including one extreme position to prevent movement of the movable member away from the jaw and effective in its opposite extreme position to permit movement of the movable member away from the jaw, a removable padlock for holding the latch in said one extreme position, spring means biasing said rotary member and thereby said latch to an intermediate position in said range of positions, said spring means being effective upon removal of the padlock to move the rotary member and latch to said intermediate position, a first cam on said rotary member, a follower for said first cam, electrical contacts operated by the follower, said cam and follower being effective when the rotary member is moved from said one extreme position to said intermediate position to operate said contacts, a locking dog movable between a locking position wherein it lies in the path of a portion of said rotary member and prevents movement thereof past said intermediate position toward said other extreme position and an unlocking position wherein it permits free movement of the rotary member, time-controlled means for moving said locking dog to its unlocking position a predetermined time after operation of the time-controlled means is initiated, a second cam on the rotary member, means including the second cam for initiating operation of the time-controlled means as the rotary member is moved to its intermediate position, and a finger operatively connected to the rotary member for forcibly moving the locking dog to its locking position as the latch is moved to said one extreme position.

4. Apparatus for locking a movable member comprising a casing, a jaw on the casing for engaging the member, a latch pivotally mounted on the casing, a rotary member in said casing and directly connected to the latch for concurrent movement therewith, said latch and rotary member being movable between two extreme positions, said latch being effective when in a range of positions including one extreme position to prevent movement of the movable member away from the jaw and effective in its opposite extreme position to permit free movement of the movable member away from the jaw, a removable padlock for holding the latch in said one extreme position, spring means biasing said rotary member and thereby said latch to an intermediate position in said range of positions, said spring means being effective upon removal of the padlock to move the rotary member and latch to said intermediate position, a first cam on said rotary member, a follower for said first cam, electrical contacts operated by the follower, said cam and follower being effective when the rotary member is moved from said one extreme position to said intermediate position to operate said contacts, a locking dog movable between a locking position wherein it lies in the path of a portion of said rotary member and prevents movement thereof past said intermediate position toward said other extreme position and an unlocking position wherein it permits free movement of the rotary member, time-controlled means for moving said locking dog to its unlocking position a predetermined time after operation of the time-controlled means is initiated, a second cam on the rotary member, means including the second cam for initiating operation of the time-controlled means as the rotary member is moved to its intermediate position, and a finger operatively connected to the rotary member for forcibly moving the locking dog to its locking position as the latch is moved to said one extreme position.

5. Apparatus according to claim 3, in which said spring means comprises telescoping sleeve and rod elements, a pair of spring retainers slidably mounted on the rod element, a spring between said retainers biasing them apart, stop means on the rod element for limiting the travel of each retainer in a direction away from the other, said retainers being slidable within the sleeve element, means on the sleeve element for limiting the travel of each retainer in a direction away from the other retainer, a pivotal connection between one end of one element and the casing and a pivotal connection between the opposite end of the other element and the rotary member.

6. Apparatus according to claim 3, including a stop formed on the casing to limit movement of the locking dog in a locking direction so as to prevent movement thereof beyond its locking position.

7. Apparatus according to claim 4, in which said first cam has opposed cam surfaces and said follower has opposed follower surfaces for engaging the respective cam surfaces so that the follower is positively operated in both directions, said positive follower operation insuring movement of the finger to force the locking dog to its locking position.

8. An electrical circuit controller, comprising

a casing, a cover for the casing having depending edge portions to provide a recessed central portion, bracket means attached to the casing and extending upwardly and inwardly to the recessed central portion of the cover, an insulating terminal board attached to the bracket means within said recessed portion, terminal posts mounted on the board so as to be readily accessible upon removal of the cover, cooperating movable and stationary contacts electrically connected to said terminal posts and depending downwardly from said terminal board, said movable contacts extending downwardly beyond said stationary contacts, an operator for said movable contacts comprising an insulating member extending parallel to said board and engageable with said movable contacts, a support for said insulating member mounted for pivotal movement about an axis parallel to said board, cam follower means attached to said support, and a cam rotatable about an axis parallel to said board for operating said follower means to move said movable contacts into and out of engagement with said stationary contacts.

9. Apparatus for locking a movable member comprising a casing, a jaw on the casing for engaging the member, a latch pivotally mounted on the casing, a rotary member mounted within one end of said casing and directly connected to the latch for concurrent movement therewith, said latch and rotary member being movable between two extreme positions, said latch being effective when in a range of positions including one extreme position to prevent movement of the movable member away from the jaw and effective in its opposite extreme position to permit free movement of the movable member, a removable padlock for holding the latch in said one extreme position, spring means biasing said rotary member and thereby said latch to an intermediate position in said range of positions, said spring means being effective upon removal of the padlock to move the rotary member and latch to said intermediate position, a first cam on said rotary member, a follower for said first cam, an electrical circuit controller mounted in the central portion of the casing and operated by the follower, said cam and follower being effective when the rotary member is moved from said one extreme position to said intermediate position to operate said controller, a locking dog movable between a locking position wherein it lies in the path of a portion of said rotary member to prevent movement thereof past said intermediate position toward said other extreme position and an unlocking position wherein it permits free movement of the rotary member, time-controlled means within the casing at the end opposite the rotary member for moving said locking dog to its unlocking position a predetermined

60

time after operation of the time-controlled means is initiated, an elongated locking bar extending from the time-controlled means along one side of the casing and carrying said locking dog at its extremity, and means for initiating operation of the time-controlled means as the rotary member is moved to its intermediate position.

10. Apparatus as in claim 9, including a cover for the casing having depending edge portions to provide a recessed central portion, and bracket means attached to the casing and extending upwardly and inwardly to the recessed central portion of the cover; and in which said circuit controller comprises an insulating terminal board attached to the brackets means within said recessed portion of the cover, terminal posts mounted on the board so as to be readily accessible upon removal of the cover, cooperating movable and stationary contacts depending downwardly from the terminal board and electrically connected to the terminal posts, said movable contacts extending downwardly beyond the stationary contacts, an operator for said movable contacts comprising an insulating member extending parallel to the board and engageable with said movable contacts, and a support for said insulating member and said cam follower mounted for pivotal movement about an axis parallel to said board.
- 15 30 35 40 45 50
11. Apparatus according to claim 9, in which said means for initiating operation of the time-controlled means includes a releasing member adjacent said time-controlled means and movable between a holding position wherein it prevents operation of the time-controlled means and a released position wherein it permits operation of the time-controlled means, a second cam on the rotary member, a second follower for said second cam, and a connection between the second follower and the releasing member, said second cam and follower being effective when the rotary member moves to its intermediate position from said one extreme position to move the releasing member to its released position.
